By A. Miller Reedfield, Atty

UNITED STATES PATENT OFFICE

PAUL F. WILLIAMS, OF CHICAGO, ILLINOIS, ASSIGNOR TO G & W ELECTRIC SPECIALTY CO., OF CHICAGO, ILLINOIS, A CORPORATION OF ILLINOIS

ELECTRICAL CONNECTER

Application filed June 17, 1922. Serial No. 569,057.

My invention relates to electrical connectors, particularly of the kind commonly known as potheads.

One of the objects of the invention is to provide a simple, practical and advantageous construction of device of the class specified.

Another object of the invention is to simplify and improve the connecting devices by which the electrical conductors are connected with one another.

In the accompanying drawings Fig. 1 is a vertical section of a pothead embodying my present invention;

15 Fig. 2 is a cross section taken on line 2-2 in Fig. 1;

Fig. 3 is a view of a detail of construction.

In the accompanying drawings I show a pothead of the single conductor type, but 20 it will be understood that the invention is applicable to potheads of other kinds and varieties.

Referring to the drawings, I show a structure comprising a lower member 1 and upper member 2, both preferably made of porcelain and the member 2 being preferably in the form of a cap to fit on top of and to some extent extend down upon member 1. The member 1 is to receive the cable and 25 the member 2 to receive the overhead conductor which is to be connected with the cable. A terminal 3 for the cable is arranged within the upper part of tubular member 1. The cable conductor is understood to be secured as by soldering to the lower end (not shown) 30 of this terminal 3. Another terminal 4 is located in a recess 5 in the upper end of the cap member 2, this terminal 4 being for the overhead conductor 6. The terminal 4 is provided with a downwardly extending plug portion 7, the lower portion of which is screw threaded as at 8. Threaded washers 9 and 10 hold the plug member 7 and therefore the terminal 4 firmly in position in cap member 2. A secondary plug member 11 is secured to the lower end of member 7, as by providing it with a threaded end 12 adapted to fit into the threaded socket 13 in the lower end of member 7. Member 11 is provided 35 with an enlarged head 14 adapted to fit into

socket 15 at upper end of terminal 3. A sleeve 16 is fitted over member 7, being inferiorly threaded to screw on threads 8 of member 7. Lower end of sleeve 16 is split as at 16^a so as to permit it to slide readily into and out of socket 15 in terminal 3, thereby making an electrical connection and breaking the same. Member 11, particularly head 14 thereof, is for taking up an arc, should any be formed on breaking circuit. 40 Ring 19 is screwed on upper threaded end 18 of terminal 3, and also forms an arc taking member. By making members 11 and 19 removable, they may be readily replaced and new ones substituted when worn or 45 damaged.

Threaded nut 20 is arranged on terminal 3 to cooperate with internal flange 21 on member 1 and also with member 19 to hold terminal 3 in position in member 1.

The arrangement forms a very simple, practical and effective construction for making and breaking the circuit, and for taking up arcs in case there are any formed in operation of the device.

It will be understood that changes and modifications may be made without departing from the spirit of the invention.

What I claim is:

1. A device of the class specified having separable outside members provided with terminals, said terminals having electrical contact members for making and breaking connection, and one of said terminals being provided with an arcing device which engages the terminal and also engages the corresponding outside member to hold the terminal in position.

2. A device of the class specified having separable outside members provided with terminals, said terminals having electrical contact members for making and breaking connection and one of said terminals having an arcing device engaging the terminal and also engaging one of the outside members.

3. A device of the class specified having a tubular insulating member and a cap of insulating material detachably mounted on the upper end of said insulating member, terminals for said insulating member and said cap,

the terminal of the insulating member having a socket at the end nearest the cap member, a plug member carried by the cap terminal, said plug member having its lower portion 5 screw threaded, an interiorly threaded sleeve fitted over said threaded plug member, the lower end of said sleeve being split and being adapted to fit into the socket of said tubular member terminal, threaded collars on said 10 tubular member terminal and means on the tubular member for engaging said threaded collars.

4. A device of the class specified having a tubular insulating member and a cap of insulating material detachably mounted on the 15 upper end of said insulating member, terminals for said insulating member and said cap, the terminal of the insulating member having a socket at the end nearest the cap member, a plug member carried by the cap terminal, said plug member having its lower portion 20 screw threaded, an interiorly threaded sleeve fitted over said threaded plug member, the lower end of said sleeve being split and being adapted to fit into the socket of 25 said tubular member terminal, threaded collars on said tubular member terminal and means on the tubular member for engaging said threaded collars, said means comprising 30 an inwardly projecting rim on the tubular member.

5. A device of the class specified having a tubular insulating member and a cap of insulating material detachably mounted on the 35 upper end of said insulating member, terminals for said insulating member and said cap, the terminal of the insulating member having a socket at the end nearest the cap member, a plug member carried by the cap 40 terminal, said plug member having its lower portion screw threaded, an interiorly threaded sleeve fitted over said threaded plug member, the lower end of said sleeve being split and being adapted to fit into the socket of said 45 tubular member terminal, a detachable arcing terminal on said plug terminal enclosed except at its end by said threaded sleeve and a detachable arcing ring on said insulator terminal adapted to cooperate with the arcing 50 terminal on the plug member.

6. In a device of the class specified, the combination with separable outside members of a terminal for a conductor located in one of said members and having a screw threaded 55 end, an arcing annular member having a threaded socket adapted to engage said threaded end of said terminal, an annular shoulder within said outside member and an annular member having a threaded bore and 60 located on the side of said shoulder opposite said arcing annular member to hold the terminal in place.

7. A device of the class specified having separable outside members provided with 65 terminals, said terminals having plug and

socket electrical contact members for making a breaking connection and the plug member having a separable arcing terminal to take up the effect of arcs at break, and a socket terminal having means for engaging its contact member and also having a shoulder adapted to engage a shoulder on the containing outside member.

In witness whereof, I hereunto subscribe my name this 12th day of May, A. D. 1922.

PAUL F. WILLIAMS.
